UNITED STATES PATENT OFFICE.

JOHN A. BASSETT, OF SALEM, MASSACHUSETTS, ASSIGNOR TO THE AMERICAN STEAM GAS COMPANY.

IMPROVEMENT IN THE MANUFACTURE OF ILLUMINATING-GAS.

Specification forming part of Letters Patent No. 36,254, dated August 19, 1862.

To all whom it may concern:

Be it known that I, JOHN A. BASSETT, of Salem, in the county of Essex and State of Massachusetts, have invented certain Improvements in the Manufacture of Illuminating-Gas from Steam, of which the following is a full, clear, and exact description, reference being had to the accompanying drawing, making part of this specification, in which is represented a vertical section through the apparatus which I employ, the brick-work and furnace not being shown.

On the 3d day of January, 1860, I obtained Letters Patent of the United States for improvement in the manufacture of hydrocarbon gas, in which the steam after being decomposed by contact with the incandescent coke or charcoal was thrown together with the vapor of some hydrocarbon into a second heated retort where the two were further decomposed and united, and a durable and rich gas was produced with the consumption of an exceedingly small amount of hydrocarbon.

My present invention is an improvement on the above; and it consists in passing superheated steam into a retort containing bituminous coal, partly incandescent and partly in a bituminous state, the incandescent part serving to decompose the steam as it comes in contact with it, and the bituminous part, which is only heated but not incandescent, furnishing to the hydrogen gas from the decomposed steam the carbon necessary to render it illuminating, or the balance which may be necessary, and which has not been obtained from the incandescent coal. The gas produced in this retort may be passed through another heated retort for the purpose of still further uniting the hydrogen gas with the carbon; or, as described in my aforesaid patent, it may pass directly to the purifier and thence to the gasometer.

To enable others skilled in the art to understand and use my invention, I will proceed to describe the manner in which I have carried it out.

In the said drawings, A represents a steam-boiler from which steam is conducted through the pipe *a*, which is bent or coiled in the furnace or flue, so that the steam in passing through it may be thoroughly superheated, to a verti-

cal retort, B, which is also heated by the furnace or flue. This retort in which the bituminous coal is to be placed has a hopper, C, on top of it. The lid *b* of the hopper is removable to fill it, and a cock, *c*, which has a hole through it is used to drop a charge of the fine coal with which the hopper is filled into the retort at intervals, as may be required, to replace the coal which is consumed in or is removed from the lower part of the retort. A horizontal pipe, D, at the bottom of the retort has on its end a cap or lid, *d*, which may be opened to draw out at intervals the coke and cinders resulting from the burning of the coal.

The brick-work, in which the boiler is usually set, and the flues are not represented here, as various arrangements of these can be made, as well as changes in the relative positions of the boiler and retort to suit convenience or to economize space. The cock *c* may be turned at intervals, either by hand or by some machinery, where such is handy, to drop a charge of fine coal into the retort and keep the coal at a proper height in the retort, so that while the coal in the lower part of the retort is in an incandescent state, that near the top of the retort will be only heated but not burning.

The pipe *a* enters the retort near its lower end, so that the superheated steam comes directly into contact with the incandescent coal, by which it is decomposed. The hydrogen gas now rises through the coal in the top of the retort, from which it collects a further supply of carbon necessary to render it illuminating, it having collected but a small portion in its first contact with the incandescent coal. The carbureted hydrogen gas then passes off by the pipe *f* to the purifier and thence to the gasometer, or it may be first passed through another heated retort, when necessary, to make the combination of the carbon more perfect and durable.

I do not wish to confine myself to this particular form of retort, (although I consider it the best,) nor to the particular construction or arrangement of the several apparatus connected therewith, as these may be varied without departing from the spirit of my invention. For example, a horizontal retort may be used to contain the incandescent coal, and another one above it may contain the coal through

which the gas is to be passed, each being supplied at intervals with coal; and instead of using fine coal in the hopper C, coal may be prepared in pieces or blocks of a convenient size to be dropped at intervals into the retort. I generally use the best bog-head cannel coal; but a poorer quality of gas-producing coal may be used and a small quantity of coal or resin tar be added. The steam by being thoroughly superheated before it enters the retort does not cool down the incandescent coal and check the decomposition of the steam, while the gas thus produced passes in a highly-heated state up through the coal in the top of the retort, and the gases produced in these two parts of

the retort readily unite and pass off at f in a gas containing the requisite amount of carbon to make a rich illuminating-gas.

What I claim as my invention, and desire to secure by Letters Patent as an improvement in the manufacture of illuminating-gas, is—

Passing superheated steam into a retort containing carbonaceous material partly in an incandescent and partly in a bituminous state, substantially as set forth.

JOHN A. BASSETT.
